United States Patent Office

Des. 233,367
Patented Oct. 22, 1974

233,367

STILL CAMERA OR SIMILAR ARTICLE

Robert E. Bourke, Weston, Conn., assignor to
GAF Corporation, New York, N.Y.

Filed Nov. 29, 1972, Ser. No. 310,436

Term of patent 14 years

Int. Cl. D16—01

U.S. Cl. D61—1 B

Fig. 1

Fig. 2

Fig. 3

Fig. 4

FIG. 5

FIG. 6

FIG. 7

FIG. 1 is a front perspective view of a still camera or similar article showing my new design;

FIG. 2 is a front elevational view thereof;

FIG. 3 is a top plan view thereof;

FIG. 4 is a left side elevational view thereof;

FIG. 5 is a bottom plan view thereof;

FIG. 6 is a right side elevational view thereof;

FIG. 7 is a rear elevational view thereof.

I claim:

The ornamental design for a still camera or similar article, as shown.
